UNITED STATES PATENT OFFICE.

ROBERT MOTT DE VIGNIER, OF HOLLIS TERRACE, NEW YORK, ASSIGNOR TO WESTERN ELECTRIC COMPANY, OF NEW YORK, N. Y., A CORPORATION OF ILLINOIS.

SEMAPHORE-SIGNALING SYSTEM.

1,104,480.

Specification of Letters Patent.

Patented July 21, 1914.

Application filed March 23, 1912. Serial No. 685,899.

To all whom it may concern:

Be it known that I, ROBERT MOTT DE VIGNIER, citizen of the United States, residing at Hollis Terrace, in the county of 5 Queens and State of New York, have invented a certain new and useful Improvement in Semaphore-Signaling Systems, of which the following is a full, clear, concise, and exact description.

10 This invention relates to semaphore signaling systems, and more particularly to a semaphore signaling system in which the signals are moved to danger position under control of a distant operator and manually 15 returned to normal or safety position.

The invention has for its object the provision of a simple form of answer-back mechanism adapted to be operated in the 20 operation of the semaphore signal and one 25 which will be reliable in its operation and not liable to injury by the comparatively massive parts of the semaphore signal.

In the application of this invention to a 30 semaphore signal a lost motion connection is provided between the answer-back mechanism and a vertically movable member of the semaphore whereby the said answer-back mechanism will be rendered operative only when the semaphore arm has reached 35 a danger indicating position. This lost motion connection comprises a rotating member operated by the vertically movable rod and carrying lugs, one of which is adapted in the rotation of said member to raise a holding pawl which releases a spring driven 40 shaft. The resetting of the answer-back mechanism occurs in the return of the signal to normal position and is accomplished through the return rotation of the said rotation member the lugs of which engage pins extending from the face of a disk carried 45 by the spring driven shaft to rewind the spring and return said shaft to the position where it is held by said pawl.

45 In the drawings illustrating this invention—Figure 1 is a front elevation with parts in section of the answer-back mechanism; Fig. 2 is a side elevation illustrating the connection of the mechanism to the vertically movable rod of the semaphore. Figs. 3 and 4 are fragmentary details of parts of the mechanism; and Fig. 5 is a view in side elevation with parts broken away of a semaphore signal and the answer-back mechanism.

Referring now to said drawings, and particularly to Fig. 1, 5 designates a clock train interrupting mechanism which may be any well-known form, such as a district messenger call-box. This mechanism comprises 60 as a part a cover 6, a motor shaft 7 connected with a chain of gears, and spring-contacts 8, 9 and 10 rendered operative in the operation of said gear train. The motor shaft 7 extends through one side of the 65 cover, and there is mounted upon the outer end thereof a disk 12 having a notch 13 in its periphery and diametrically oppositely located pins or projections 14, 14 in its face. Pivotaly supported adjacent to said 70 disk is a pawl 15 adapted to engage the notch 13 and having a projecting portion 16 which extends over the face of the disk 12 for the purposes hereinafter set forth. The mechanism is mounted upon a suitable 75 support 17 which is preferably a part of the semaphore signal support.

Supported in a bearing 20 carried by said support 17 is a shaft 21 upon the inner end of which and adjacent to the disk 12 is 80 mounted a clutch member 22 having lugs 23 and 24 thereon adapted to engage the pins 14, 14 on the disk 12 and the projecting portion 16 of the pawl 15 in the rotation of 85 said shaft. Mounted upon the outer end of the shaft 21 is a forked member 25 having prongs 26 and 27 and a shoulder 28 adapted, in the downward movement thereof, to engage a stop member 29 secured to said base 17. An antifriction roller 35 secured to the 90 vertically movable rod 40 of a semaphore signal is in engagement with the forked member 25 between the prongs 26 and 27 thereof.

A portion of the surface of the vertically 95 movable rod 40 is provided with rack teeth 45, 45 adapted to mesh with a toothed segment 46 mounted upon a shaft 47 rotatably supported in bearings 48, 48. Also rotatably mounted upon said shaft 47 is a collar 49 100 carrying a handle 50 having a projecting portion 51 thereon adapted to engage a projection on the toothed segment 46 to return the semaphore arm 52 to normal position. The vertically movable rod 40 moves in engagement with an antifriction roller 35. 105

Referring now to the operation of the mechanism, it will be assumed that the semaphore arm 52 is in normal or safety position, as indicated in full lines in Fig. 5, and that 110

the necessary steps have been taken to release the semaphore arm. When released the weight of the arm and the vertically movable rod will cause said rod to move 5 downwardly, and as it moves downwardly the engagement of the roller 35 in the forked member 25 will cause the rotation of the shaft 21 and clutch 22 in a counter-clockwise direction, as indicated by the arrow in Fig. 4. As the clutch 22 is rotated the lug 24 thereon will be brought into engagement 10 with the projecting portion 16 of the pawl 15 and will lift said pawl from engagement with the notch 13 in the disk 12, thus releasing said disk and permitting the motor 15 shaft 7 to rotate and close suitable circuits through the contact springs 8, 9 and 10. The lug 24 upon the clutch 22 is so located 20 with respect to the pawl 15 that it will not engage the projection 16 thereon until the vertically movable rod 40 has fallen almost, if not quite, to the limit of its downward movement; at least, until the semaphore arm 50 has reached a position indicating 25 danger.

When the clock train mechanism is released by the lifting of the pawl 15 the disk 12 will be rotated until the pins 14, 14 thereon are in engagement with the back faces of the lugs 23 and 24 on the clutch member 22. As the vertically movable rod 40 moves downwardly it will rotate the toothed segment 46 into the position shown in dotted lines on Fig. 5. The member of the train 30 crew who responds to the signal restores the parts to normal by pulling the handle downwardly. This rotates the toothed segment 46 to lift the rod 40. As the rod 40 moves upwardly the antifriction roller 35 thereon 35 engages the prong 26 of the forked member 25, and thus rotates the clutch member 22 which, as it rotates, carries the disk 12 therewith by reason of the engagement of the pins 14, 14 thereon with the lugs 23 and 24 on 40 said clutch member. This movement of the disk 12 will bring the notch 13 into position to be engaged by the pawl 15, which is normally pressed against the periphery of said disk by means of a spring 60. At the same 45 time that the pawl 15 drops into the notch 13 of the disk 12 suitable retaining mechanism is moved into engagement with the rod 40 of the signal, and all parts are in condition for a succeeding operation.

50 By controlling the release of the answer-back mechanism through the pawl 15 and the clutch 22, as hereinbefore described, the said answer-back mechanism is free from shock or other detrimental effects due to the 55 movement of the comparatively massive parts of the semaphore signal. Furthermore, the relation of the answer-back mechanism to the vertically movable rod 40 makes possible the release of the answer-back mechanism at any point of the movement of said

rod desired merely by the changing of the relation of the lug on the clutch 22 to the pawl 15 and the pins on the disk 12. It is desirable, however, in a system of this class that this operation do not occur until the 70 semaphore arm has reached a position where the desired signal cannot be mistaken.

I claim:

1. In combination a semaphore signal, an operating member therefor having a reciprocal movement, current interrupting mechanism, and a rotating member operatively connected with said operating member and said current interrupting mechanism for both releasing and resetting said current interrupting mechanism in the reciprocal movement of said operating member. 75

2. In a semaphore signaling system the combination with a semaphore arm and a vertically movable rod connected therewith, of current interrupting mechanism embracing a shaft and driving means carried thereby, a disk carried by said shaft and having a notch therein, a pivotally mounted pawl normally engaging said notch, a projection on said pawl extending over the face of said disk, a rotating member located adjacent said disk and operatively connected with said vertically movable rod, and a lug on said rotating member brought into engagement with the projecting portion of said pawl when said rod is substantially at the limit of its downward movement. 85

3. The combination with a semaphore signal comprising a semaphore arm and a vertically movable rod connected therewith, of current interrupting mechanism embracing a shaft and driving means therefor, a disk secured to said shaft and having a notch therein, pins projecting from the face of said disk, a spring-pressed pawl engaging said notch, a projection on said pawl extending over the face of said disk, a rotating member operatively connected with said vertically movable rod, and a pair of lugs on 105 said rotating member, one of said lugs being adapted when the said rod is substantially at the limit of its downward movement to lift said pawl from engagement with the notch, and both said lugs being adapted 110 to engage the pins in said disk in the upward movement of said rod to reset said interrupting mechanism. 115

4. The combination with a semaphore signal comprising a semaphore arm and a vertically movable rod connected therewith, of current interrupting mechanism embracing a clock-train, a support for said interrupting mechanism, a forked arm mounted upon said support and operatively connected with 120 said vertically movable rod for both releasing and resetting said current interrupting mechanism, and means for limiting the downward movement of said forked member. 125

5. The combination with a semaphore sig- 130

nal comprising a semaphore arm and a vertically movable rod connected therewith, of current interrupting mechanism embracing a clock-train, a support for said interrupting mechanism, a forked arm mounted upon said support and operatively connected with said vertically movable rod for both releasing and resetting said current interrupting mechanism, a shoulder on said member and a stop on said support adapted to be engaged by said shoulder.

5 In witness whereof, I hereunto subscribe my name this 21st day of March A. D., 1912.

ROBERT MOTT DE VIGNIER.
